UNITED STATES PATENT OFFICE.

CHARLES GANTERT, OF ROCK ISLAND, ILLINOIS.

REVOLUBLE SHOW-CASE.

SPECIFICATION forming part of Letters Patent No. 726,900, dated May 5, 1903.

Application filed January 9, 1903. Serial No. 138,384. (No model.)

To all whom it may concern:

Be it known that I, CHARLES GANTERT, a citizen of the United States, residing at Rock Island, in the county of Rock Island and State of Illinois, have invented certain new and useful Improvements in Revoluble Show-Cases, of which the following is a specification, reference being had therein to the accompanying drawings.

- o My invention relates to revoluble showcases; and it is my object to provide a showcase of this type with a series of hinged doors or closures having spring-latches which are automatically operated by revolving the case to unlock each door as it arrives at a given point—as, for example, when the several doors reach a point facing the operator behind the counter they become unlocked.

I have shown my invention as applied to an upright revolving case for exhibiting plug tobacco having a division in the middle; but I do not confine myself to this type of revolving show-case, as it is evident my invention is adapted to other types of revolving cases.

In the accompanying drawings, forming a part of this specification, Figure 1 is a front elevation of the revolving show-case mounted upon a pedestal. Fig. 2 is a central vertical section of said case and its pedestal, showing the locking mechanism and means for operating the same. Fig. 3 is a top plan view of the top of the pedestal, and Fig. 4 is a bottom plan view of the show-case.

Referring more particularly to the drawings, A denotes an upright revoluble showcase, and B a pedestal upon which said case is mounted. The case proper is composed of a top piece A¹, bottom piece A², and partition A³, framed in with four uprights or risers A⁴, forming an octagonal frame with an upper and lower compartment, which are separated by the partition A³.

A⁵ denotes eight glass doors the frames of which are hinged to the risers A⁴ and provided with catches a. The bottom A² is provided with a central bearing a', which registers with a journal projecting from the top of the pedestal. It is also provided with four friction-rollers a'', which ride upon a track, hereinafter mentioned. C denotes four arms pivoted midway of their length to bearings c,

secured to said bottom piece. c' denotes four friction-wheels secured at one end of said arms C, the other ends of said arms being pivoted to four vertical plungers D, which pass through the bottom piece and extend upward through the lower compartment and the partition A³ to about midway of the upper compartment, as shown in Fig. 2.

B¹ denotes a journal mounted centrally to the top of the pedestal and registers with the bearing a' in the bottom of the show-case in which it revolves.

B² denotes a circular track fastened to the top of the pedestal on which the friction-wheels a'' bear.

B³ denotes a shoe or short raised track with beveled ends mounted to the top of the pedestal outside of the circular track in the path of the friction-wheels c'. Said wheels c' in their normal position strike the track B³ and ride over it, as hereinafter mentioned.

The plungers D are preferably divided about midway of their length and their ends united by turnbuckles D'. The upper ends of each plunger are threaded and provided with threaded collars, which are thereby adjustable vertically.

E denotes metal plates fastened to the risers about midway of their length, provided with pivoted latches e, which engage catches a. Said catches have projecting ends e', which are perforated to admit the passage of the upper ends of the plungers D.

e² denotes coiled springs secured to plates E and fastened to projecting ends of said latches. The tension of said springs is such that the plunger-rods are drawn up to their normal place, and in this position of the plungers the glass doors of the revolving case are held locked. This position of the plunger-rods also holds upward the end of the arms C, to which it is attached, and thus holds down the opposite ends of said arms carrying the friction-wheels c', so that as the show-case is revolved said wheels will contact with and ride over the shoe B³.

The show-case being mounted upon the pedestal and the several parts being adjusted as described, they will operate as follows to unlock each one of the glass doors as they arrive in turn opposite the point desired. The pedestal is arranged with the shoe B³ at the

point desired where the doors are to be unlocked. As the case is revolved the nearest friction-wheel in turn will engage with the track B and riding up and over it will pull 5 down the end of the arm C which carries the plunger D. As the plunger D moves downward its collar will bear down upon the outer or projecting end of the latch, and its inner end will thus be raised from engagement with 10 the catch a. Thus each door in turn will be automatically unlocked as it reaches the position mentioned.

Having thus described my invention, what I claim, and desire to secure by Letters Patent, is—

- 15 1. A rotary show-case having a series of hinged doors arranged with spring-latches a series of plungers connected to said latches and means for operating said plungers in rotation to unlock said latches at a given point at each revolution of said case.
- 20 2. In a rotary show-case the combination of the hinged doors, latches for said doors, plun-

ger-rods connected to said latches, springs for actuating said plunger-rods in one direction, pivoted arms connected to said plunger-rods for actuating the same in the opposite direction, and means for actuating said arms in rotation at a given point to unlock said latches.

25 3. In a revolving show-case the combination of the hinged doors, the latches, the plunger-rods, the springs attached to said latches and plunger-rods, the pivoted arms attached to the bottom of the show-case having one end connected to the plunger-rods and their 30 free ends projecting below the case and a stationary shoe arranged exterior of the show-case and in the path of the free ends of said pivoted arms and adapted to rock the arms in rotation at a given point.

35 In testimony whereof I affix my signature in presence of two witnesses.

CHARLES GANTERT.
